UNITED STATES PATENT OFFICE.

FREDERICK MICHAEL AND ROBERT WILLIAMS, JR., OF EATON, OHIO.

MAIL-BAG.

SPECIFICATION forming part of Letters Patent No. 296,429, dated April 8, 1884.

Application filed February 16, 1884. (No model.)

To all whom it may concern:

Be it known that we, FREDERICK MICHAEL and ROBERT WILLIAMS, Jr., both of Eaton, in the county of Preble and State of Ohio, have 5 invented a new and Improved Mail-Pouch, of which the following is a full, clear, and exact description.

The object of our invention is to provide a new and improved mail-pouch which can be 10 opened, closed, locked, and unlocked very readily, which is simple in construction, and not apt to get out of order.

The invention consists in a mail-pouch provided in the edge of each side, at the opening, 15 with a longitudinal pocket for receiving welts secured on a sliding cover-piece, whereby the sides of the pouch are drawn together and the pouch closed by passing the cover and welts into the pockets. A hasp is secured on the 20 sliding cover, and is adapted to be locked in place by a combined lock and tag holder on the side of the pouch.

Reference is to be had to the accompanying drawings, forming part of this specification, 25 in which similar letters of reference indicate corresponding parts in all the figures.

Figure 1 is a side view of the upper part of our improved mail-pouch. Fig. 2 is a plan view of the same. Fig. 3 is a cross-sectional 30 view of the same on the line *x x*, Fig. 1. Fig. 4 is a perspective view of the combined lock and tag holder.

The pouch A has each side formed of two thicknesses, B' B², at the mouth, and to the inner surface of each thickness or layer B' B² a 35 welt, C, of leather or other suitable material, is secured, a slot being formed between the inner surfaces of the welts.

To the outer surface of each layer B' B² a 40 metal strip or plate, D, is fastened, which is provided with a bend or shoulder, E, at about the middle of its height. As the said plates are secured to the layers B' B², shoulders will also be formed in the layers B' B², thus forming 45 pockets F between the bottom edges of the welts and the shoulders. A U-shaped piece, G, of leather or metal, has a welt, H, of leather, cord, &c., secured to each surface along the free edges, which welts are of such size that 50 the two on the same side of the piece G fit into one of the pockets F, formed in the upper edges

of the sides of the pouch in the manner described. A hasp, H², is held by a staple, H', on one end of the top piece, G, and to the opposite end a handle-loop, J, is fastened. The 55 plates or strips D extend beyond the side edge of the bag, as shown in Fig. 1.

A casing, K, is riveted to the outer surface of the pouch at one of the side edges, and the said casing is provided with a hinged top, L, 60 provided with a slot, L', and adapted to receive a tag or ticket, M. At the free end of the top L the sides of the casing K are provided with notches N, for receiving the cross-piece at the free end of the hasp H², and the top L is provided with a transverse groove, O, in its under side, at the free end. Under the swinging top L springs are provided for throwing it upward. The casing K is provided with a sliding bolt, P, for locking the cover or top L on 70 the casing K, which bolt can be operated by a lock mechanism contained in the part K' of the casing.

The pouch is locked and unlocked in the following manner: To lock the pouch, the mouth 75 edges of the pouch are pressed together, and the cover G is drawn longitudinally over the mouth in such a manner that the welts H H pass into the pockets below the welts C. There- 80 by the edges of the mouth of the pouch will be held together and the pouch closed. The hasp H is then swung down, so that its cross-piece passes into the notches N of the casing K, and then the cover L is swung down to close the casing K and hold the hasp in the casing. If 85 the cover L is swung down, the bolt P snaps into an opening in a cross-piece of the cover and locks the cover on the casing. The hasp is thus locked in place and prevents withdraw- 90 ing the cover-piece G from the longitudinal pockets in the edges of the mouth of the pouch. At the same time it prevents tampering with the tag or exchanging or removing the same. If the pouch is to be opened, the cover L is 95 unlocked and springs outward, the hasp H is swung up, and the cover-strip G withdrawn by means of the handle-loop J. As the plates or strips D project beyond the side edges of the pouch, the cover can be withdrawn sufficiently to open the mouth of the pouch completely; 100 but the cover-piece G will still be held on the pouch by the projecting parts of the strips or

plates D. If the plate did not project, the cover-piece would have to be withdrawn entirely from the pouch, or the mouth of the pouch could not be opened completely.

5 The hasp H can also be used as a handle in closing the pouch—that is, in drawing the cover-piece G over the mouth to close it.

By means of the above-described device the bag can be closed very effectually and rapidly.

10 It will be almost water-proof, and cannot open accidentally.

Having thus described our invention, we claim as new and desire to secure by Letters Patent—

15 1. The combination, with a pouch having longitudinal pockets formed in its edges at the mouth, of a cover-piece provided with welts adapted to pass into the pockets and close the pouch, a hasp on the cover-piece, and means for locking the hasp on the pouch, substantially as herein shown and described.

20 2. The combination, with a pouch, of a sliding cover-piece for closing it, a hasp on the cover-piece, and a lock-casing secured to the pouch and adapted to receive and hold the free end of the hasp, substantially as herein shown and described.

25 3. The combination, with a pouch, of a slid-

ing cover-piece for closing the pouch, a hasp on the sliding cover-piece, and a combined 30 lock-casing and tag-holder secured on the pouch, substantially as herein shown and described.

4. The combination, with a pouch, of the welts C, the shouldered plates D, the cover-piece G, and the welts H on the same, substantially as herein shown and described.

5. The combination, with the pouch A, of the welts C, the cover-piece G, the welts H, secured to the same, and of the shouldered plates 40 or strips D, projecting beyond the end edges of the pouch, substantially as herein shown and described.

6. The combination, with a mail-pouch, of a sliding cover-piece, a hasp on one end of the 45 same, the lock-casing K, provided with notches N, the cover L, provided with the transverse groove O, and of a bolt-and-lock mechanism for locking the cover in place, substantially as herein shown and described.

FREDERICK MICHAEL.
